UNITED STATES PATENT OFFICE

91,439

DESIGN FOR A PLUMBING FIXTURE

William Wallace Potter, Pawtucket, R. I.

Application May 2, 1932. Serial No. 43,696

Term of patent 3½ years

To all whom it may concern:

Be it known that I, WILLIAM WALLACE POTTER, a resident of Pawtucket, county of Providence, State of Rhode Island, and a citizen of the United States, have invented a new, original, and ornamental Design for Plumbing Fixtures, of which the following is a specification, reference being had to the accompanying drawing, forming a part thereof.

In the drawing:

Fig. 1 is a front elevational view;
Fig. 2 is a side elevational view; and

Fig. 3 is a perspective view of a plumbing fixture, showing my new design.

The dominant features of my design are the circular body with its swelled-out front, the central handle, the centrally located nozzle, and the valves at diametrically opposite sides of the central circular body.

I claim:

The ornamental design for a plumbing fixture, as shown and described.

In testimony whereof I hereunto affix my signature. WILLIAM WALLACE POTTER.
